CLAIM

The ornamental design for a frame for respiratory mask, as shown.

DESCRIPTION

FIG. 1 is a front perspective view of a frame for respiratory mask showing our new design;
 FIG. 2 is a front view thereof;
 FIG. 3 is a rear view thereof;
 FIG. 4 is a top view thereof;
 FIG. 5 is a bottom view thereof;
 FIG. 6 is a left side view thereof; and,
 FIG. 7 is a right side view thereof.
